CLAIM

The ornamental design for a pop shaped hairstick, as shown and described.

DESCRIPTION

FIG. 1 is a top, front, and right side perspective view of a pop shaped hairstick having a tapered end, showing my novel design;

FIG. 2 is a left side elevational view thereof, all sides appearing the same;

FIG. 3 is a top plan view thereof;

FIG. 4 is a bottom plan view thereof;

FIG. 5 is a top, front, and right side perspective view of a second embodiment wherein the modification resides in the blunted configuration of the tip;

FIG. 6 is a front elevational view thereof, all sides appearing the same;

FIG. 7 is a top plan view thereof; and,

FIG. 8 is a bottom plan view thereof.
